By

UNITED STATES PATENT OFFICE

ROBERT E. POWERS, OF NEW YORK, N. Y., ASSIGNOR TO UNIVERSAL DRAFT GEAR ATTACHMENT CO., A CORPORATION OF ILLINOIS

ANGLE-COCK HOLDER

Application filed January 12, 1928. Serial No. 246,167.

This invention relates to railway equipment and more particularly to angle cock holders.

One of the objects of the invention is the provision of new and improved means for preventing the disengagement of the angle cock from its holder.

Another object of the invention is the provision of a cock holder having novel means for securing the angle cock thereto together with new and improved means for preventing the disengagement of the holder from its support should the holding nuts accidentally become disengaged.

15 Other and further objects and advantages of the invention will appear from the following description taken in connection with the accompanying drawings, in which

Fig. 1 is a vertical section of an end sill of 20 a railway car showing the invention in position thereon;

Fig. 2 is a section on line 2—2 of Fig. 1;

Fig. 3 is a section on line 3—3 of Fig. 1; and

25 Fig. 4 is a section on line 4—4 of Fig. 1.

Referring now to the drawings, in which the same reference numerals are employed to designate similar parts throughout the specification, the reference numeral 10 designates 30 the end sill of a railway car and 11 a bracket attached to said sill for constituting a support for the angle cock holder 12. An angle cock of the usual or any well known construction is shown at 13. The angle cock is provided with the usual polygonal end 14 for receiving a wrench for turning the angle cock for attaching it to the end of a pipe 15 in the usual manner.

The holder 12 comprises a plate or body 40 portion 16 slotted at its lower portion as at 17 for receiving the attaching U-bolt 18 as will presently appear. The holder 12 may be considered as comprising two plates spaced apart by the web portions 20. The holder 12 may 45 have a lateral extension 30 provided with a seat having angular sides for receiving the upper portion of the polygonal member 14 for preventing turning of the angle cock.

The body portion 16 is provided with a 50 transverse opening 19 through which the pipe

15 is adapted to extend. The opening is in communication with the upper end of the slot as clearly shown in Fig. 3.

The holder has upwardly extending portions 21 and 22 provided with inwardly opening grooves for receiving the laterally bent or extending end 23 of the supporting bracket 11, the parts being so arranged that when the holder is on the bracket the laterally extending end 23 will engage the upper face of 60 the extension 30.

Suitable means are provided for preventing the holder 12 from sliding off the bracket 11. As shown a U-bolt is employed for this purpose. The U-bolt is adapted to extend 65 beneath the pipe 15 within the slot 17. The threaded ends of the bolt extend through aligned openings 24 and 25 in the body portion 16 and laterally extending end 23 of the bracket support 11, respectively. Nuts 26 on 70 the upper ends of the U-bolt 18 are adapted to be tightened to cause the loop of said bolt to grip the pipe 15.

It is not an uncommon occurrence for nuts 75 that hold the angle cock holder assembled on its bracket to become accidentally loosened and lost, thus permitting the holder to become disengaged from its supporting bracket. It is desirable that means be provided to prevent the disengagement of the bolt 80 even though both nuts work loose and become lost. In the form of the device selected to illustrate one embodiment of the invention, a gravity operated pin 27 is employed for this purpose. An inclined guide in the form 85 of a bore 28 is provided through one side of the member 12. Preferably, though not necessarily, a lug 29 is provided on the side of the member 12 and the bore 28 extends through this lug. The bore is so located that 90 the pin will extend beneath the U-bolt 18 for supporting it from dropping low enough to become disengaged from the bracket end 23 even though the nuts 26 become detached.

The bore 28 is at such an incline that gravity 95 will cause the pin to slide downward into contact with the opposite side wall of the slot 17 beneath the pipe 15.

If desired, a keeper 300 may be provided for preventing the removal of the pin 27, 100

surreptitiously or otherwise. The keeper is adapted to be bent entirely over or partially over the opening 28, whereby the pin cannot be removed until the keeper is bent back out of the path of the pin.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. An angle cock holder comprising a supporting bracket, a holder member slidably mounted on said bracket, said member having its lower portion slotted and provided with a pipe opening extending transversely therethrough and in communication with said slot, said bracket and member being provided with aligned openings, a U-bolt in said slot and having its end portions extending through said openings, and means engaging in said slot below said bolt for preventing withdrawal of said bolt.

2. An angle cock holder comprising a supporting bracket having openings therethrough, a holder member slidably mounted on said bracket and having its lower portion slotted and provided with a pair of apertures extending through said member from said slot in alignment with said openings, a retaining member extending through said apertures and openings, nuts on the upper ends of said member, and a pin extending into the slotted portion of said bracket for preventing the disengagement of said member from said openings and apertures upon the accidental disengagement of said nuts from said member.

3. An angle cock holder comprising a member having an open ended slot in its lower portion and provided with an opening extending across said member transversely to said slot and in communication therewith, said member also being provided with one or more openings communicating with said slot and said first mentioned opening for receiving a fastening member, and having a diagonal aperture for receiving a pin, said aperture communicating with said slot below said first mentioned opening.

4. An angle cock holder comprising a bracket member, a holder member provided with a pipe opening extending transversely therethrough, means for securing said holder member to said bracket member, and a gravity operated member for preventing the disengagement of said means from said members.

5. An angle cock holder comprising a bracket member, a holder member slidably mounted on said bracket member, said holder member having a pipe opening extending

transversely therethrough, a U-bolt extending upwardly through said bracket and holder members and adapted to clamp a pipe extending through said opening, and a gravity operated member slidably mounted on said holder member and adapted to be projected by gravity beneath said bolt to prevent its accidental disengagement from said bracket and holder members.

In testimony whereof I affix my signature.

ROBERT E. POWERS.
